CLAIM

The ornamental design for a tool handle grip, as shown and described.

DESCRIPTION

FIG. 1 is a perspective view of a tool handle grip showing our new design;
FIG. 2 is a top plan view thereof;
FIG. 3 is a bottom plan view thereof;
FIG. 4 is a front elevational view thereof;
FIG. 5 is a side elevational view thereof, the opposite side elevational view being a mirror image; and,
FIG. 6 is a rear elevational view thereof.

FIG - 1

FIG-2

FIG-3
